UNITED STATES PATENT OFFICE

WILLIAM F. TRIPPLETT, OF GRAND JUNCTION, COLORADO

AEROPLANE PROPELLER

Application filed March 19, 1930. Serial No. 437,216.

This invention relates to aeroplane propellers and has as its primary object to provide a propeller which will furnish a uniform flow of air at all speeds in a take-off of the aeroplane and in straight flight, and which will likewise reduce or substantially eliminate the usual drumming or droning noises attending the operation of an ordinary propeller.

Another object of the invention is to provide a propeller which will reduce the liability of stalling in flight inasmuch as it creates in flight, as stated, uniform flow of air at any speed of the engine.

This invention also consists in certain other features of construction and in the combination and arrangement of the several parts, to be hereinafter fully described, illustrated in the accompanying drawings and specifically pointed out in the appended claims, it being understood that minor changes may be made so long as they fall within the scope of the claims.

In describing my invention in detail, reference will be had to the accompanying drawings wherein like characters denote like or corresponding parts throughout the several views, and in which:

Figure 1 is a view in side elevation of a propeller embodying the invention.

Figure 2 is a front elevation thereof.

Figure 3 is a detail vertical transverse sectional view taken substantially on the line 3—3 of Figure 1 looking in the direction indicated by the arrows.

Figure 4 is a transverse sectional view taken substantially on the line 4—4 of Figure 3 looking in the direction indicated by the arrows.

Figure 5 is a transverse sectional view through one of the blade units taken on the line 5—5 of Figure 1 looking in the direction indicated by the arrows.

In the drawings the numeral 1 indicates the propeller shaft and the numeral 2 indicates a head which is of metal and which is mounted upon the propeller shaft and held for rotation therewith by a key 3. The head is formed in diametrically opposite sides with recesses 4 in its intermediate portion and

between cylindrical portions 5 and the said recesses serving purposes which will presently be explained. Each propeller blade comprises a main blade 6 which is of any suitable material and which is formed with a longitudinally extending opening indicated by the numeral 7 and the said openings of the two blades extend from a point near the outer ends of the blades to the head 2. The blades 6, at their inner ends and at opposite sides of the inner end of each opening 7 are provided each with offset portions 8 which are disposed against one side of a respective one of two pairs of lugs 9 formed integrally with the head at diametrically opposite sides of its portions 5, and plates 10 are disposed against the other sides of the lugs 9 and rivets or other securing elements 11 are secured through the offset portions 8, the plates 10 and the lugs 9, and in this manner the blades 6 are connected at their inner ends for rotation with the shaft 1, it being observed that each plate 10 is likewise secured by a rivet or other suitable fastening element 12 to the respective inner end portion of the respective blade 6.

In addition to the blades 6 which are directly rotated by the shaft 1 and which shaft is in turn rotated by the motor of the aeroplane, each blade unit comprises an auxiliary blade which is indicated in general by the numeral 13 and these auxiliary blades are of a length equal approximately to the length of the openings 7 and of a width nearly equal to the width of said openings so that the blades 13 may be received within the openings for rotary motion in a manner to be presently explained. Each blade 13 preferably has its longitudinal edge portions curved in opposite direction as indicated at 14.

Mounted in each bearing ball race 15 which is of annular form and the numeral 16 indicates a cap plate which is disposed against the side of the head 2 in which the respective recess 4 is formed, so that the bearing race 15 will be held within the recess, the plate 16 being formed with a symmetrical opening 17. The numeral 18 indicates shanks which extend from heads 19

which are of circular form and each of these heads is provided with a short cylindrical stud 20 which fits in an opening 21 formed centrally in a ball bearing race member 22 which is in the nature of a circular disk, the stud 20 being headed or overturned as indicated by the numeral 23 so as to be connected with the head 19 of the shank 18. The bearing race 15 and bearing race 22 are suitably 5 grooved in their mutually opposing sides as is also the inner peripheral portion of the head 19 and bearing balls 24 are arranged within the annular race thus formed as a unit.

15 Each shank is formed with two flat sides indicated by the numeral 24' and these flat sides are arranged planes converging in the direction of the outer end of the shank 18. Each blade 13 is tapered at its inner end and this tapered inner end is slightly deflected as at 25 to provide a portion 26 which is disposed against one of the sides 24. A plate 27 is disposed against the other side 24 of each shank 18 and rivets 28 are secured 20 through the portion 26 of each blade, through the tapered portion of the respective shank and through the respective plate 27 and in this manner the inner ends of the blades 13 are connected with the shank so that they 25 will rotate with the head 19.

It will be observed by reference to Figures 1 and 5 of the drawing that in one position of the blades 13, the blades are substantially located within the openings 7 in the respective 30 blades 6 but due to the curvilinear contour of their longitudinal edge portions 14, they will, when the propeller, as a whole, is rotated, be caused to rotate rapidly. It will be evident that the blades 13 will be rotated 35 at a greater speed, about an axis at right angles to the axis of the rotation of the shaft 1 than the speed at which the blades 6 are rotated in the atmosphere and that the blades 13 will not only be rotatable with respect to the blades 6 but also rotatable with 40 the said blades 6. Due to this construction and arrangement of parts the rotation of the propeller blades will create a uniform flow of air at all speeds, not only in the take-off 45 of the aeroplane, but also in straight flight and due to the fact that the blades rotate axially of the blades 6, the noises usually 50 created by blades of the same type as the blades 6 but imperforate, will not be produced.

In actual tests on a $\frac{1}{4}$ horsepower motor at 55 17,050 revolutions per minute and using a propeller constructed from alloy steel and measuring two feet long and five inches wide, 60 it has been found the air will be smoothed out at various speeds of the motor from 800 revolutions per minute up to 17,050 revolutions per minute. These tests were made from different angles from the natural flow 65 of wind current. This condition is created

by the small blades being free to revolve by velocity and at an increased speed from the main blade which is connected to the drive shaft of the motor, which revolution speed will govern the main blade speed. 70 With a straight propeller blade constructed to pull or worm its way through the air as it cleaves the air at a speed that varies from 250 to 300 revolutions per minute from climbing to cruising speed it disturbs the natural flow of air current. The highly disturbed air current in rushing and returning to its normal state from the pulling edges of the propeller under the present constructions 75 creates the drone or sharp drum noises. The propeller blade hereinbefore described, by the small blade revolving independently and at an increased rate of speed, will create a small flow of air current inside of the main current as created by the main blade in cleaving the current of flow of this highly disturbed air, thus fanning and retarding the air as it attempts to return to its original natural flow, thus dulling the sharp drone 80 and drum. In other words, to convey the idea, the construction hereinbefore described will act as a silencer as the highly disturbed air can not rush back in its natural state at a high rate of compact. Under actual tests 85 in the placing of small holes to lead or move ahead of the main blade edges it will increase the efficiency and further reduce the noises heretofore mentioned and not retard the efficiency of the main blade. 90

95 What I claim is:—

1. An aeroplane propeller comprising a hub, blades radiating therefrom and each comprising a fixed main blade rotatable with the hub and provided with a longitudinal opening therein, and an auxiliary blade mounted in the opening of each main blade and rotatable therein about an axis radial to the axis of rotation of the hub, each auxiliary blade having its longitudinal marginal portions deflected in opposite directions whereby to offer resistance to air currents and whereby the said auxiliary blade will be rotated with respect to the main blade by the air currents passing through said opening. 100

110 2. An aeroplane propeller comprising a hub, blades radiating therefrom and each comprising a fixed main blade rotatable with the hub and provided with a longitudinal opening therein, and an auxiliary blade mounted in the opening of each main blade and rotatable therein about an axis radial to the axis of rotation of the hub, each auxiliary blade having its longitudinal marginal portions curved in opposite directions whereby 115 to offer resistance to air currents and whereby the said auxiliary blade will be rotated with respect to the main blade by the air currents passing through said opening. 120

3. An aeroplane propeller comprising a hub, blades radiating therefrom and each comprising a fixed main blade rotatable with the hub and provided with a longitudinal opening therein, and an auxiliary blade mounted in the opening of each main blade and rotatable therein about an axis radial to the axis of rotation of the hub, each auxiliary blade having its longitudinal marginal portions curved in opposite directions whereby to offer resistance to air currents and whereby the said auxiliary blade will be rotated with respect to the main blade by the air currents passing through said opening, the said marginal portions of each auxiliary blade projecting beyond opposite sides of the main blade.

4. An aeroplane propeller comprising a hub, blades radiating therefrom and each comprising a fixed main blade rotatable with the hub and provided with a longitudinal opening therein, an auxiliary blade associating with each of the main blades and including a shank having a rotatable bearing in the respective side of the said hub, whereby to provide for free rotation of the auxiliary blade with respect to the main blade and about an axis radial to the axis of the hub, each auxiliary blade having a portion offering resistance to air currents, whereby the said auxiliary blade will be rotated with respect to the main blade by the air currents passing through said opening.

In testimony whereof I affix my signature.
